UNITED STATES PATENT OFFICE

AARON ZAUDER, OF BROOKLYN, NEW YORK

CONTAINER

Application filed July 14, 1928. Serial No. 292,855.

This invention relates to tubes which serve as containers for various materials that are to be gradually used, the most common form of such tubes being the ordinary flexible tube 5 having a cap closure at its upper end and so constructed that when the cap is removed and the other end of the tube is squeezed or rolled up, the contents of the tube are gradually forced out through the delivery opening. 10 Other tubes are made to use the contents by tearing off a portion of the delivery end of the tube adjacent to the contents to expose the contents, such tubes being usually used only with solid, or comparatively solid, contents. 15 In almost every existing form of tube for use with such things as tooth paste, shaving cream, cosmetics, make-up materials for actors, etc., there is some objectionable feature in the provisions for getting the material out 20 of the tube. In the ordinary squeeze or roll-up form of tube there is considerable waste of materials which is left in the irregular recesses in the tube and in other forms of tubes there is usually more or less smearing of the 25 hands in getting the contents out.

An object of the present invention is to provide an attachment for tubes which may be put on and sold as a part of the tube structure itself and which will be an improvement 30 over means heretofore known for effecting the removal of the tube contents.

More particularly, the invention aims to provide means for causing the ejection of the tube contents which in itself will constitute a 35 closure for one end of the tube and which in its operation will sever a portion of the tube corresponding to the amount of material ejected, thus maintaining the tube constantly 40 full and of a length suitable to contain the remaining contents.

Other objects and important features of the invention will appear from the following description and claims when considered in connection with the accompanying drawings, in 45 which

Figure 1 is a view, partly in section, of an ordinary tube for paste or material of similar consistency, having a relatively small delivery opening normally closed by a screw cap

and having the present invention applied to its other end;

Figure 2 is a view, partly in section, illustrating the invention applied to a tube of the same cross-sectional dimensions throughout 55 its length and closed at its delivery end by a slip-on cap;

Figure 3 is a view somewhat similar to Figure 2 but showing a section of the attachment at right angles to the section shown in Figure 2 and having the delivery end of the tube provided with a screw-on cap; and

Figure 4 is a bottom plan view of the construction.

For convenience in assembling the parts 65 and in placing the attachment in position on the tube, it is preferably made of two main parts comprising an outer cylindrical shell 2 and an inner shell 4 between which the lower end of the tube 6 is confined. The inner shell 70 4 is provided with a screw thread 7 of rounded cross-section so that it will not cut the material of the tube, and the outer shell 2 is provided with a protuberance 8 which fits into the depression between the threads of the inner shell 4, the protuberance 8 being also rounded and preferably formed by indenting the shell 2.

Upon the upper end of the inner shell 4 rests a washer or disk 10 which bears against the 80 under side of the contents 12 of the tube, which contents may be in the form either of paste or of substantially solid material. In the drawings, the upper end of the shell 4 is also shown as closed at 14, but it will be obvious that a complete or even partial closure of this end of the shell is not necessary so long as sufficient bearing surface for the washer 10 is provided.

In order that the two shells may cooperate 90 to push the washer 10 up the tube and thus force the tube contents out of the upper end of the tube, the shells are connected together to turn together so that the screw thread formation on the inner shell will cause the shells 95 to travel up the tube and the protuberance 8 on the outer shell 2 cooperating with the thread on the inner shell will form a thread in the tube as the shells travel up the tube, the tube being preferably made of material 100

adapted to be readily deformed. The illustrated means for connecting the two shells together comprise lugs or projections 16 extending from the lower edge of the inner shell 4 through openings 18 in the head of the outer shell 2 and upset or headed over the outer face of the outer shell.

It is obvious that the lower end of the tube must be disposed of as the connected shells travel up the tube, and to this end the attachment is provided with cutting means which serve to trim off an amount from the lower edge of the tube corresponding to the distance of travel of the attachment up the tube. The illustrated cutting means comprises a knife blade 20 struck up from a steel disk 22 provided with openings 24 through which the lugs 16 extend so that the disk 22 is connected to the shells 2 and 4 to turn therewith. The knife blade 20 extends through a recess 26 in the inner shell 2 into the tube-receiving space between the shells where it engages the tube and as the shells turn together and travel up the tube severs spirally from the lower edge of the tube a strip 28. The head of the outer shell is provided with an opening 30 through which the strip 28 is discharged so that as the contents of the tube are used up and the material of the tube is cut away, the portion of the strip 28 that projects beyond the head of the shell 2 may be turned off and thrown away, thus leaving the tube with substantially its original appearance except for its vertical height. From the foregoing description it will be seen that by merely grasping the outside of the tube and turning the attachment on its lower end, the desired amount of the tube contents may be forced from the upper end without any apparent deformation of the tube and without liability of smearing the hands with the tube contents. Moreover, the tube itself is used up at fast as its contents and the contents can be more gradually removed than with the ordinary tube construction because of the greater control and therefore precision of the operation of the means for effecting ejection of the contents.

When the tube is intended for paste, a form similar to Figure 1 may be used; when the contents of the tube are somewhat more solid, then either the form shown in Figure 2 or that shown in Figure 3 is preferable, in which the removable cap is of the same diameter as the tube so as to permit the contents of the tube to be moved bodily up the tube.

In Figure 2 of the drawings, it will be noted that the inner shell 4, which serves as a plunger for forcing the material out of the tube, extends above the upper edge of the outer shell 2, thus permitting the tube contents to be forced completely out of the tube while still leaving a sufficient portion of the tube to be gripped by the hand to permit rela-

tive turning of the tube and the contents ejecting attachment.

What is claimed as new is:

1. A container comprising a tube of material adapted to be readily deformed, a closure located in one end of the tube, provided with a tube-wall-engaging thread, and into threaded engagement with which the adjacent portion of the wall of the tube is deformed, and means carried by said closure and engaging the opposite face of the tube wall for depressing a portion of the tube wall into the thread groove of said closure. 70

2. A container comprising a tube of material adapted to be readily deformed, a closure located in one end of the tube, provided with a tube-wall-engaging thread, and into threaded engagement with which the adjacent portion of the wall of the tube is deformed, means carried by said closure and engaging the opposite face of the tube wall for depressing a portion of the tube wall into the thread groove of said closure, and means also carried by said closure and operating as said closure is turned in said tube to cut from the lower edge of the tube a portion corresponding in vertical dimension to the length of travel of the closure lengthwise of the tube. 80

3. A container comprising a tube presenting a substantially smooth inner surface, a closure located in one end of the tube and closely engaging the walls thereof, said closure being provided with an external thread in threaded engagement with the tube wall whereby the closure travels longitudinally of the tube as it is turned in the tube, and cutting means carried by said closure and so located that it cuts from the closure end of the tube a portion of the tube corresponding to the length of travel of the closure along the tube. 95

4. A container comprising a tube of material adapted to be readily deformed, a closure comprising concentric outer and inner shells between which a portion of the tube wall is confined and by which it is deformed, said shells having cooperating portions acting to deform the tube wall to provide a screw thread cooperating with a corresponding thread on one of said shells whereby as said closure is turned in said tube it will travel lengthwise of said tube at the same time forming in said wall a continuation of the wall thread. 110

5. A container comprising a tube of material adapted to be readily deformed, a closure comprising concentric outer and inner shells between which a portion of the tube wall is confined and by which it is deformed, said shells having cooperating portions acting to deform the tube wall to provide a screw thread cooperating with a corresponding thread on one of said shells, the inner shell having a plunger end extending toward the delivery end of said tube a sufficient distance 125 130

beyond the corresponding end of the outer shell to permit gripping of the tube as said plunger approaches the delivery end for effecting a relative turning of the tube and the closure.

5 6. A container comprising a cylindrical tube formed of material adapted to be readily deformed and presenting a substantially smooth inner surface for contact with the 10 contents of the container, a plunger located within the tube and movable lengthwise thereof from the base of the tube toward the discharge end thereof to force material from the tube and means movable with reference 15 to the tube for forcing the plunger lengthwise of the tube, and an element carried by said means and engaging the tube for reducing the length of the tube as said means is moved lengthwise thereof.

20 7. A container comprising a cylindrical tube formed of deformable material and presenting a substantially smooth inner surface for contact with the contents of the tube, said tube being formed with threads on a portion 25 thereof, a plunger fitting closely within the tube, means engaging the threads on said tube and movable lengthwise thereof to force the plunger and tube contents lengthwise of the tube, and a cutting element carried by said 30 means for cutting material from said tube as said means is moved lengthwise thereof.

35 8. A container comprising a tube formed of material adapted to be readily deformed, said tube presenting a substantially smooth inner surface for contact with the contents of the container, a plunger located within the tube and closely fitting the walls thereof, means associated with said plunger engaging the tube wall for deforming a portion of the 40 wall to produce a thread therein, and a threaded member carried by said means for engaging the threads so formed in the tube and operating when turned to move the plunger and contents lengthwise of the tube.

45 9. A container comprising a cylindrical tube presenting a substantially smooth inner surface for contact with the contents of the container, a plunger fitting closely within the tube, and means carried by the plunger for 50 forming a spiral groove in the wall of the tube when rotated relative thereto, and means for engaging said groove to effect longitudinal movement of the plunger when rotated with reference to the tube to force the plunger 55 against the tube contents and eject the latter from the tube.

60 10. A container as defined in claim 9 which further comprises means operated by the rotation of the plunger with reference to the tube to sever a strip from the tube substantially equal in width to the longitudinal movement of the plunger in the tube.

65 11. A container comprising a cylindrical tube presenting a substantially smooth inner surface for contact with the contents of

the container, a cylindrical plunger having a smooth cylindrical portion fitting closely within the cylindrical walls of the tube and a portion having a spiral groove, and means carried by the plunger externally of the tube 70 for engaging a portion of the walls of the tube and forcing it into said groove, whereby a rotation of said plunger will effect a longitudinal movement therein with reference to the tube to force tube contents lengthwise of 75 the tube.

Signed at New York, N. Y., this 10th day of July, 1928.
